CLAIM

The ornamental design for a bottle, as shown and described.

DESCRIPTION

FIG. 1 is a perspective view of a first embodiment of a bottle showing our new design;

FIG. 2 is a perspective view of a second embodiment of the bottle;

FIG. 3 is a side elevation view of the bottle depicted in FIG. 2;

FIG. 4 is another side elevation view thereof;

FIG. 5 is a front elevation view thereof;

FIG. 6 is a back elevation view thereof;

FIG. 7 is a top plan view thereof;

FIG. 8 is a bottom plan view thereof; and,

FIG. 9 is a perspective view of a third embodiment of the bottle.

The dashed line shown in the drawings is for illustrative purposes only and forms no part of the claimed design.

The dot-dash-dot line shown in the drawings defines the boundary of the claim and forms no part of the claimed design.
